UNITED STATES PATENT OFFICE.

WALES ALDRICH, OF MIAMISBURG, OHIO, ASSIGNOR TO ABEL HOOVER AND WM. GAMBLE, OF SAME PLACE.

GRAIN-BINDER.

SPECIFICATION forming part of Letters Patent No. 274,692, dated March 27, 1883.

Application filed January 4, 1883. (No model.)

To all whom it may concern:

Be it known that I, WALES ALDRICH, of Mi-
amisburg, in the county of Montgomery and
State of Ohio, have invented certain new and
useful Improvements in Grain-Binders, of
which the following is a specification.

My invention relates to machines wherein the
binding mechanism is automatically started by
the pressure of the accumulating gavel, and
more particularly to such as have the general
structure of that type commonly called the
"Appleby Binder." In this the binder-arm is
supported upon a rock-shaft below the deck-
ing of the grain receptacle or chute, this chute
being inclined from the receiving to the dis-
charge side. The grain, as it enters the chute,
is forced forward by packers till it strikes and
accumulates against a compressing finger or
fingers supported upon an arm beneath the
decking and normally closing the exit from the
receptacle; but rocking upon a pivot upon said
arm, as the grain accumulates, it will finally, by
acting upon a lever, cause the binding devices
to be tripped or set in motion, when the cord is
immediately carried around the gavel and its
ends united, and the supporting-arm, swinging
downward, by its positive action carries the
compressing-fingers momentarily out of the
way and allows the bound sheaf to be dis-
charged. The binder-arm and the supporting-
arm for the tripping or compressing fingers are
driven by a train of cog-gearing from the con-
stantly-rotating shaft connected with the har-
vester. The upper wheel of this train is a gear
and cam wheel keyed to the shaft which actu-
ates the knotter, and connected with the rock-
shaft of the binder by means of a wrist-pin and
pitman, and also to a rock-shaft, which at the
proper time depresses the supporting-arm by
means of another pitman, preferably formed
with yielding sections, said latter pitman be-
ing attached to one arm of a T-shaped lever
pivoted by its longer arm to the frame-work,
and taking, by a pin or anti-friction roll upon
the second arm of its head, into a cam-track
upon the wheel, whereby it is actuated only at
the proper moment after the binding operation
is completed. I have found a tendency, when
this machine is used in the field, to a reverse
or backing action in the gearing at times when
it should be positively at rest, which is due

either to the sagging of the heavy binder-arm
or to the jar of the machine, or, perhaps, in
some instances, to the pressure of the gavel
upon the compressing-fingers, resulting in a 55
downward force upon the supporting-arm. In
order to overcome this tendency, I propose to
apply a positive stop or lock, which shall come
into effective play at the moment the binder
reaches its position of rest, and absolutely pro- 60
hibit any retrograde action; and I will pro-
ceed to describe, for the purpose of illustrating
my invention, the most desirable embodiment
of said locking device at present known to me.

In the drawings, Figure 1 is a front end ele- 65
vation of a machine of the above-recited type
having said locking device applied thereto, and
Fig. 2 a section on the correspondingly-num-
bered line in Fig. 1.

A is the continuously-rotating driving-shaft, 70
from which motion is communicated directly
to the packing-arms, and B a pinion mounted
loosely thereon, and acted upon by the usual
tripping-clutch, b, to engage it with said shaft,
and thereby drive, by the intermediate gear- 75
pinions, C and D, the gear and cam wheel E,
which, by means of its wrist-pin e and the pit-
man F, is connected with a crank from the
rock-shaft G, carrying the binder-arm. This
gear and cam wheel, to lighten it and relieve 80
it of dead matter, has usually been made of
skeleton form—that is, such material as can
be spared without decrease of strength is re-
moved, leaving a series of holes, e', with webs
of metal between, connecting the rim and the 85
hub.

H is the T-lever, pivoted by its longer arm,
h, to the frame-work of the machine, and con-
nected, by a pin on one of its shorter arms, h',
and the yielding pitman I, with a crank from 90
the rock-shaft K, this latter shaft having a link-
connection with the supporting-arm for the
compressing and tripping fingers, so as to re-
tract it or return it to place, according to the
motion of the shaft. The second short arm, h², 95
of the T-lever is provided with a pin or roll en-
tering the cam-track e² in the wheel, whereby
said lever will be operated by the revolution
of the wheel to communicate the appropriate
motions to the yielding pitman, and thence to 100
the supporting-arm and compressing-fingers.
Upon the long arm of the lever is formed a

shoulder, h^3 , at such a point that when the binding mechanism is brought to its position of rest this shoulder will be opposite one of the perforations e' in the wheel. A plate-spring, 5 L, is bolted or riveted to the body of the wheel, to one side of the perforations, a seat being formed for it in said body, so that it may be attached by a single bolt, and the free end of this spring is bent down to pass through the 10 c perforation and come at its point in line with the shoulder on the lever. This spring is so arranged relatively to the lever and to the direction of motion of the wheel that when the wheel is revolved to operate the binding mechanism it will at the outset carry the spring 15 away from the shoulder; but as the revolution is being completed, the spring, being brought again to the lever, but on the opposite side of the shoulder, will be pushed aside by the latter, and immediately thereafter will snap down behind it in its original position, the wheel at the 20 same moment ceasing its revolution. It will now be impossible for any retrograde motion to take place, since the spring, resting against said shoulder, will prevent the gear and cam wheel 25 from returning in the direction from which it has come, and will permit it only to be moved

forward in the direction in which it will cause the binding mechanism to operate, and such latter motion will take place only when the 30 machine is tripped by the accumulation of the gavel.

I claim—

1. The combination, substantially as herein-before set forth, with the gear and cam wheel 35 and the lever operated by its cam-track, of a locking device between said wheel and lever, adapted to prohibit the motion of said wheel except in that direction in which it properly actuates the binding mechanism.

2. The combination, substantially as herein-before set forth, of the gear and cam wheel, the lever operated by its cam-track, the shoulder upon an arm of said lever, and the spring attached to said wheel, and arranged to pass said shoulder as the wheel moves in its proper direction, and to snap behind it as the wheel comes to rest, and thereby prohibit retrograde motion. 45

WALES, ALDRICH.
